US00D907389S

(12) **United States Design Patent** (10) **Patent No.:** **US D907,389 S**
(45) **Date of Patent:** **** Jan. 12, 2021**

(54) **CHAIR**

- (71) Applicants: **Maruni Wood Industry Inc.**,
Hatsukaichi (JP); **Jasper Morrison**,
London (GB)
- (72) Inventor: **Jasper Morrison**, London (GB)
- (73) Assignee: **MARUNI WOOD INDUSTRY INC.**,
Hiroshima (JP)
- (**) Term: **15 Years**
- (21) Appl. No.: **29/708,161**
- (22) Filed: **Oct. 3, 2019**

(30) **Foreign Application Priority Data**

- Apr. 5, 2019 (JP) 2019-007503
